221.

Dear Mr. City, N.Y.

Letter Patent

X 9511

The Schedule is referred to in this Letters Patent and making part of the same, containing a description of the tools of the said James Mc. Cleay himself of his Improvement in the Door-Block.

It is known that I James Mc. Cleay of the City County and State of New York have made an improvement in the Door-Block which will be briefly as follows. Referring to my Hall to the annexed drawings of the same making part of this Specification. The block or case A of the block is made similar to that of common use, within the case are placed two sets of guards B, each guard having a slot to which two stones working on prominent studs D, B, set in the plate E of the block to keep the stones in their places. In the upper edge of each guard is a notch C to receive the block hereafter described, these notches are made at different distances from the edge of the guard. Between every pair of guards is placed a plate F, the F being turned to slide independently of each other. In the upper or outer plate of tin a Spring I is made to press against to a permanent stud K on this spring may be suspended with these guards are three hinged vertically backward and forward by a key L, having two bits M, N each consisting of a series of steps or projections of different heights corresponding in number to the guards in which they act. The handle of the key, P, is made hollow in order to pass over a slide pin set in the plate, in which times when the block is worked sideways one side, but when worked on both sides there must be a bearing for the key in the usual manner on both sides there are two keys, O, P, for returning the guards to their former positions. A lock lever T is passed through the end, placed in the plate and one connected together by a bar, Q, having a projection R, in its center to receive the key acts. There are two blocks S, T, turning vertically on pins placed in the plate, the upper side of each block has a projection S, which gives into a corresponding notch in the lower edge of the bolt, and on the under side of said block is a similar projection T which drops into the

notches of the guards A & a rectangular piece of metal or round bar at B is placed between the guards and the bolt to shut off all communication from the safety key hole with the bolt A plate of iron C turning on a pivot is connected at one end to one of the checks by a small projection which drops into a groove in the check for covering the key hole of the bolt key keepers described. The bolt D is made something similar to the common bolt but has two notches E on its lower edge to admit the check to ride into them by which it is secured and an opening F to admit the bolt key. If thick it is thrown forward and back. The key F by which the bolt is moved is made in two parts. The first part consists of a key bit G which fits into the opening in the bolt for turning it. The second part consists of the safety key H having a tooth or projection I which fits into the key bit G for turning it. The key bit turning on a triangular pin fixed in the plate. Under the bolt are two springs K, &c. attached to a common timber for turning the checks into the notches of the guards A. Common lock cap L is put over the before described work secured by nuts and screws. It will be perceived that the keys are made use of with this lock one to move the bolt. - The timber place the guards in such a position that the notches in the same may correspond with each other in order that the bolt may be locked or unlocked by the bolt key. This is accomplished in the following manner. The guard key having two bits as before described each containing a number of steps differing in their lengths from the centre of the key pin. Each bit therefore has to act on a separate set of guards, which by the key is turned present a plane surface, but when the key is turned the bits come in contact with the ends of the guards which give way, & the purpose of the various steps or projections of the bit producing a similar vibration in the position of the guards but causing the notches in the same to impinge exactly on the other turning a corner from the cap L to the plate. the checks then fall into the notches from their gravity & from the action of the springs alone there. The bolt being now relieved the bolt key is inserted & turned & the bolt thrown forward. the notches of the guard key is then turned which turns the check by the action of one of the guards acting on the principle of the wedge forcing the check up into the notch of the bolt.

and then leaves it. It must be observed that in turning the guard key the plate which bears the bay hole of the bolt is removed and that, when the bolt is withdrawn or after the motion of the guard key, resume that this plate again returns to its former position over the bay hole and effectively secures it from the introduction of picks or other implements. By this last means the guard of an uniform length, and presenting an even and plain surface, the possibility of taking an impression for the purpose of making a false key is effectively prevented. And herewith the before described construction the new lock is rendered much cheaper, more durable and less liable to be picked than any lock known. All that I claim as new, and is my invention, is the before described lock, and for which I ask a patent are the guard, the plates of tin placed between them, the check to the lever and for the application of the double bitted key, to this lock and the mode of operating the several parts as before described.
